(57) **CLAIM**

The ornamental design for an adhesive wrap set for skate blade holders, as shown and described.

DESCRIPTION

FIG. 1 is a top view of an adhesive wrap set with a left side portion and a right side portion for skate blade holders showing my new design;

FIG. 2 is a bottom view thereof;

FIG. 3 is a right side view of one of the adhesive wraps of the set for skate blade holders, shown separately for the clarity of illustration;

FIG. 4 is a left side view of one of the adhesive wraps of the set for skate blade holders, shown separately for the clarity of illustration;

FIG. 5 is a rear view of one of the adhesive wraps of the set for skate blade holders, shown separately for the clarity of illustration; and,

FIG. 6 is a front view of one of the adhesive wraps of the set for skate blade holders, shown separately for the clarity of illustration.

The broken lines shown in the drawings are included for the purpose of illustrating portions of the skate blade holder to which the adhesive wrap attaches and form no part of the claimed design.
